UNITED STATES PATENT OFFICE.

JOHN P. ELLENBECKER, OF ST. CLOUD, MINNESOTA, ASSIGNOR TO GRANITE CITY ELECTRIC COMPANY, OF ST. CLOUD, MINNESOTA, A CORPORATION OF MINNESOTA.

CONTROLLING SWITCH.

Application filed March 5, 1925. Serial No. 13,173.

My invention relates to controlling switches intended for general use but especially adapted for use in connection with electrically operated cranes and the like.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view partly in side elevation and partly in longitudinal central vertical section;

Fig. 2 is a transverse vertical section taken on the line 2—2 of Fig. 1, with some parts broken away and sectioned;

Fig. 3 is a detail view of one of the members of one of the clamps and its contact plate, with some parts broken away and sectioned;

Fig. 4 is a perspective view of one of the clamps with the members thereof separated; and

Fig. 5 is a perspective view of one of the contact plates.

The numeral 6 indicates a rectangular metal housing having supporting feet 7 adapted to be bolted or otherwise secured to a support for holding the switch. The ends of the housing 6 are extended above the sides thereof and have rounded upper edges.

A displaceable cover 8 for the housing 6 rests on the chamfered upper edges of the sides of said housing and is segmental in cross section to fit the upper extended ends of said housing.

Two horizontal supporting shoulders 9 in the form of angle irons are bolted to the inner face of the ends of the housing 6 just below the upper edges of the sides of said housing. These two shoulders 9 are connected by a wide longitudinal tie bar 10 located centrally between the sides of the housing 6, and a centrally located transverse tie bar 10' is secured to the sides of said housing and connected to said tie bar 10 at their intersection. Formed in each side and each end of the housing 6 below the supporting shoulders 9 is a large aperture 11. Secured to the inner face of each end of the housing 6 above the supporting

shoulders 9 is a block 12 in which is removably mounted an anti-friction bearing 13. These bearings 13 are axially aligned and axially located intermediately between the sides of the housing 6.

A rotor assembly 14 and two co-operating contact assemblies 15 are mounted in the housing 6. This rotor assembly 14 comprises a square shaft 16 having at one end a short trunnion 17 and at its other end a long trunnion 18, an insulating sleeve 19 on the shaft 16 which is square in cross section, and a plurality of two-part metal clamps 20 (as shown four), each of which, as shown, carries diametrically opposite pairs of circumferentially spaced segmental contact plates 21. The trunnions 17 and 18 are journaled in the bearings 13 and the end of the shaft 16 engages the respective bearing 13 as a stop. The length of the shaft 16 is such that it may be moved endwise to withdraw the short trunnion from its bearing 13 for a purpose that will presently appear.

A washer 22 on the long trunnion 18 engages the inner face of the respective bearing 13 as a stop and is held in position by a cotter pin 23 inserted through a bearing in said trunnion. On the long trunnion 18 outward of the housing 6 is a wheel 24 held in position by a set screw 25. This wheel 24 has a channel-like periphery adapted to receive a rope, not shown, by which said wheel may be turned to oscillate the rotor assembly 14 either to the left or the right.

For yieldingly holding the rotor assembly 14 in neutral position and to return the same to such position there is mounted on the long trunnion 18 between the wheel 24 and respective end of the housing 6 a torsion spring 26, the arms of which normally engage opposite sides of a fixed stop pin 27 secured to the respective end of the housing 6. Secured to the wheel 24 is a pin 28 which projects between the arms of the spring 26 and yieldingly holds said wheel in normal position. When the wheel 24 is turned either to the left or the right to operate the rotor assembly 14, the pin 28 will engage one of the arms of the spring 26 and carry it with it so that when said wheel is released, the rotor assembly will be returned to neutral position. A washer 29 on the long trunnion 18 is interposed between the spring 26 and respective end of the housing 6.

The periphery of the wheel 24 is channel-shaped in cross section so as to receive a rope, not shown, by which said wheel may be turned to operate the rotor assembly 14. 5 Secured to the end of the housing 6 under the wheel 24 is a pair of rope guides 30, only one of which is shown.

The members of each clamp 20 have V-shaped half-seats 31 which fit around the insulating sleeve 19 and are adjustably connected and clamped onto said sleeve by screws 32 which extend through certain ears 33 on said members and have screw-threaded engagement with certain others thereof. 15 These screws 32 also afford means by which electric wires 34 are attached to the clamps 20. The segmental contact plates 21 are detachably secured to circumferentially spaced radial flanges 35 by screws 36, the heads of which are counter-sunk considerably below the outer faces of said contact plates.

The contact assemblies 15 are laterally spaced and the rotor assembly 14 is located therebetween. Each contact assembly 15 comprises brushes 37 arranged to be engaged by the contact plates 21 of the rotor assembly 14 when rotated from a neutral position either to the left or the right. These brushes 37 are carried by angle brackets 38 mounted on insulating members 39 and secured thereto by pairs of bolts 40. Each brush 37 is yieldingly connected to its bracket 38 by a bolt 41 on which is compressed a coil spring 42 that yieldingly presses said brush against its bracket. These brushes 37 are held in different adjustments in respect to the rotor assembly 14 by set screws 43, having lock nuts 44, which have screw-threaded engagement therewith and impinge against the brackets 38.

The brushes 37 are further yieldingly connected to their brackets 38 by flat angle springs 45 secured to said brackets by the bolts 40 and to said brushes 37 by the screws 43 and their lock nuts 44. Certain of the bolts 40 also afford means for securing the electric wires 46 to the contact assemblies 15. The contact assemblies 15 are detachably secured in the housing 6 by nut-equipped bolts 39' inserted through the ends of the insulating members 39 and the supporting shoulders 9.

Removably mounted in the housing 6 below the rotor assembly 14 and contact assemblies 15 are two laterally spaced resistance coils indicated as entireties by the numeral 47 with the exception of their flat metal cores 48 set vertically edgewise. These resistance coils 47 are removably supported on a pair of long bolts 49 equipped with nuts 50 and which bolts extend completely through bores in the sides of the housing 6 and in the projecting end portions of the cores 48. The resistance coils 47 are held

laterally spaced from each other and from the sides of the housing 6 by spacing thimbles 51 on the bolts 49. These bolts 49 are anchored against endwise movement to one of the sides of the housing 6 by means of the outer ends of the respective spacing thimbles 51 and nuts 50 which are clamped onto the opposing faces of said side. The headed ends of the bolts 49 and the respective spacing thimbles 51 extend through the bores in the other side of the housing 6 with freedom for endwise removal. The electric wires for the resistance coils are indicated by the numeral 52.

From the above description, it is evident that the rotor assembly 14 may be removed from the housing 6 by first removing the wheel 24, spring 26, washer 29 and cotter pin 23 and moving the right-hand bearing 13 inward out of the respective block 12; then, by an endwise movement of said rotor assembly to the right to withdraw the short trunnion 17 from its bearing 13. Then, by a movement of the rotor assembly 14 to the left and at the same time lifting the left-hand end thereof to clear the respective end of the housing 6, the entire rotor assembly 14 may be lifted from said housing without disturbing the contact assemblies 15. It is also evident that any one of the clamps 20 may be removed from the rotor assembly 14 by releasing its screws 32 without disturbing any of the other parts of the assembly or any one of the contact plates 21 may be removed from its clamp 20 by releasing the screws 36. It is further evident that either one of the contact assemblies 15 may be removed from the housing 6 without disturbing the other contact assembly or the rotor assembly by releasing the bolts 39' and lifting the same from said housing.

The apertures 11 are of such size that the resistance coil 48 may be removed therethrough after removing the bolts 49 and spacing thimbles 51 without disturbing any of the other parts of the switch.

The above described switch may be used in connection with electric motors that vary considerably in horse power, and any desired number of resistance coils 47 may be used simply by changing the length of the spacing thimbles 51.

What I claim is:

1. The combination with a housing having in its ends bearings, of a controlling switch including a rotor assembly, said assembly comprising a shaft having at one of its ends a short trunnion and at its other end a long trunnion, said trunnions being mounted in said bearings, the length of said shaft being such as to permit the assembly to be moved endwise to withdraw said short trunnion from its bearing.
2. The combination with a housing hav-

ing in its ends bearings, of a controlling switch including a rotor assembly, said assembly comprising an angular shaft having at one of its ends a short trunnion and at 5 its other end a long trunnion, said trunnions being mounted in said bearings, the length of said shaft being such as to permit the assembly to be moved endwise to withdraw said short trunnion from its bearing, an insulating sleeve that is square in cross section mounted on said shaft, and clamps applied around said insulating sleeve and having contact plates.

3. The structure defined in claim 2 in 15 further combination with releasable means for holding the trunnions against endwise movement in their bearings.

4. The structure defined in claim 2 in further combination with a removable operator 20 for the rotor assembly on the long trunnion outward of the housing.

5. The structure defined in claim 2 in further combination with a removable oper-

ator for the rotor assembly on the long trunnion outward of the housing, and a 25 removable torsion spring on the long trunnion, the arms of said spring normally engaging a stop on the housing, said operator having a member extending between the arms of said spring and normally holding the rotor assembly in neutral position and arranged to carry either of the arms of the 30 spring with it during a movement of the operator to return the rotor assembly to neutral position.

6. The structure defined in claim 2 in which each of said clamps comprises two 35 separable members that are adjustably connected and have angular half-seats to receive the insulating sleeve.

7. The structure defined in claim 2 in which the contact plates are removably secured to the clamps.

In testimony whereof I affix my signature.

JOHN P. ELLENBECKER.
